DESIGN FOR A LADY'S WRAP.

Design No. 18,292, dated May 1, 1888.

UNITED STATES PATENT OFFICE.

ELLEN MORAN, OF NEW YORK, N. Y., ASSIGNOR TO THE BUTTERICK PUBLISHING COMPANY, (LIMITED,) OF SAME PLACE.

DESIGN FOR A LADY'S WRAP.

SPECIFICATION forming part of Design No. 18,292, dated May 1, 1888.

Application filed April 2, 1888. Serial No. 239,333. Term of patent 3½ years.

To all whom it may concern:

Be it known that I, ELLEN MORAN, of the city, county, and State of New York, have invented and produced a new and original Design for a Pattern of a Lady's Wrap; and I do hereby declare that the engraved prints accompanying this specification convey to any one accustomed to using paper patterns a clear understanding of how a garment made up by the pattern will appear.

The design shows center fronts tapering to a point below the waist-line, side fronts curving into the arm-seyes and falling in long tabs

that widen toward the bottom, a short back tapering almost to a point at the lower edge, 15 sides falling even with the back and in square corners in front, and a standing collar.

What I claim as my invention, and desire to secure by Letters Patent, is—

The design for a lady's wrap, as shown in 20 the engraved prints accompanying this specification.

ELLEN MORAN.
